Primary Examiner — Derrick Holland*Assistant Examiner* — Jennifer O King(74) *Attorney, Agent, or Firm* — Chris Whewell(57) **CLAIM**

We claim the ornamental design for a rooftop solar parapet, as shown and described.

DESCRIPTION

FIG. 1 is a perspective view of a rooftop solar parapet; FIG. 2 is a top plan view thereof; and,

FIG. 3 is another top plan view thereof, in which the adjacent roofs are not shown for ease of illustration. The broken lines shown represent unclaimed subject matter and form no part of the claimed design.
